A new *Dianthus* plant designated 'KLEDP19309' particularly distinguished by dark red-purple single, round flowers and an upright habit, is disclosed.

1 Drawing Sheet

1

Genus and species: *Dianthus caryophyllus*.
Variety denominations: 'KLEDP19309'.

BACKGROUND OF THE NEW PLANT

The present invention comprises a new and distinct variety of *Dianthus*, botanically known as *Dianthus caryophyllus*, and hereinafter referred to by the variety name 'KLEDP19309'. 'KLEDP19309' originated from a cross from between the female *Dianthus* parent 'DSS-2014-1046' (unpatented) and the male *Dianthus* parent 'DCP-2001-TU 006' (unpatented) in The Netherlands in summer 2015.

In September 2016, 'KLEDP19309' was first vegetatively propagated by vegetative stem cuttings. 'KLEDP19309' was found to reproduce true to type in successive generations of asexual propagation in Stuttgart, Germany via vegetative stem cuttings.

SUMMARY

The following are the most outstanding and distinguishing characteristics of 'KLEDP19309' when grown under normal horticultural practices in Latina, Italy and Stuttgart, Germany.

1. Dark red-purple single, round flowers; and
2. An upright habit.

DESCRIPTION OF THE PHOTOGRAPH

This new *Dianthus* plant is illustrated by the accompanying photograph. The photograph shows the whole plant, including the flowers and foliage and buds. The colors shown are as true as can be reasonably obtained by conventional photographic procedures. The photo is of a 14-week-old plant of 'KLEDP19309'. The photo was taken in Stuttgart, Germany, indoors, in March 2017.

DESCRIPTION OF THE NEW VARIETY

The following detailed descriptions set forth the distinctive characteristics of 'KLEDP19309'. The data which

define these characteristics were collected from asexual reproductions carried out in Latina, Italy. Data was collected in May 2019 on plants that were potted in week 389 of 2018. Color references are to The R.H.S. Colour Chart of The Royal Horticultural Society of London (R.H.S.), 5th edition (2007).
